M.K. Saunders

ATTORNEY

UNITED STATES PATENT OFFICE.

WILLIAM K. ROCKMAN, OF NEW YORK, N. Y.

FOUNTAIN BRUSH.

Application filed May 20, 1925. Serial No. 31,642.

This invention relates to a fountain brush for use in forming characters and particularly for writing the Chinese language and the object of my invention is to provide such 5 a fountain brush of few parts and one wherein the ink will not flow readily except when the brush is in use.

Another object of my invention is to provide means in a fountain brush whereby 10 the bristles will not become dry and stiff when the brush is not in use.

Another object of my invention is to locate an auxiliary ink reservoir in such position in a fountain brush that an immediate 15 supply for the flow of ink to the bristles will be provided when the brush is put to use.

I accomplish the above and other objects of my invention, which will be apparent as 20 the description proceeds, by means of the device shown in the accompanying drawings, in which—

Figure 1 is a perspective of my fountain brush with the cover in position thereon;

25 Figure 2 is a perspective of the brush with the cover element thereof shown in section; and

Figure 3 is a view of the brush with the main parts thereof shown in section.

30 In the drawings, in which like characters indicate like parts on all the figures thereof, 1 indicates the holder for the ink reservoir 2. The ink reservoir 2 is preferably formed of thin rubber, the lower open end thereof 35 being fitted over a reduced portion of the tube 3. The tube 3 is preferably formed from a hard rubber substitute and serves as a distending and holding means for the open end of the ink reservoir. The holder 40 1 and the tube 3 have screw threaded engagement with each other.

Fitting within the tube 3 and held therein by friction is a tube 5 formed from metal or other suitable material. Mounted in the 45 tube 5 is an ink conductor 6, also formed of metal. The conductor 6 is provided with a small aperture in its lower extremity, which acts as an air inlet and an ink outlet for the ink reservoir.

50 Surrounding the tube 5 and forming a continuation of the tube 3 is an elongated tube 7 formed from the same material as that comprising the tube 3. The upper extremity of the tube 7 is provided with screw threads of the same pitch as those of the

tube 3. The holder 2, being provided with suitable cooperating internal screw threads, thus serves as a means for holding the parts 3, 5 and 7 in proper relation to each other. Mounted in the lower end of the tube 5 are 60 suitable bristles 8 which comprise the writing element or character forming means of the device. The bristles 8 surround a hollow metal tube 9 by means of which the ink is conducted to the bristles during use. The 65 opening through the tube 9 is of minute cross section whereby the ink will be fed in small quantities to the bristles, thus avoiding danger of the brush flooding or dropping ink.

70 During the use of the brush as a writing instrument, the conductor 6 and the tube 5 below the conductor fill with ink, the ink passing through the aperture in the lower part of the conductor to the tube 9 through 75 which it flows to the bristles.

Even when the pen is not in use, the ink remains in the tube 5 below the conductor 6, thus keeping the bristles moist and preventing their becoming stiff and dry. This 80 small auxiliary reservoir also furnishes an immediate supply for the flow of ink to the bristles when the brush is put to use.

Surrounding the bristles and serving to hold them in position with respect to the 85 remainder of the structure is a conical open ended cap 10 having frictional engagement with the tube 7.

A closure 11 is provided for the lower part of the device, which includes the bristles, when the implement is not in use. The closure 11, like the holder 1, is preferably formed from a hard rubber substitute.

Having thus fully described my invention, what I claim as new and desire to 95 secure by Letters Patent is:—

1. A fountain brush for making small characters, comprising a main ink reservoir, an auxiliary ink reservoir, means for conducting the ink from the main ink reservoir 100 to the auxiliary ink reservoir, bristles carried by said auxiliary reservoir, and means for conducting the ink from the auxiliary ink reservoir to said bristles, both of said conducting means comprising elongated tubes having valveless conducting openings of minute cross section whereby unobstructed communication between the reservoirs and bristles is maintained for keeping the bristles in moist condition. 105 110

2. In a fountain brush, a holder having a flexible ink reservoir therein, a tube secured to the lower end of said ink reservoir and detachably connected to said holder, 5 an auxiliary ink reservoir communicating with said tube, a conducting tube extending into one end of said auxiliary reservoir and

having a narrow opening thereinto, bristles and an ink conducting element therefor mounted in the opposite end of said auxiliary ink reservoir. 10

In testimony whereof I affix my signature.

WILLIAM K. ROCKMAN.
